UNITED STATES PATENT OFFICE.

CLAUDE MONTAGU TAYLOR AND EDWARD THOMAS WARMINGTON REED, OF CHELTENHAM, ENGLAND, ASSIGNEES TO WILLIAM H. COLE AND COMPANY, LIMITED, OF CHELTENHAM, ENGLAND, A CORPORATION OF GREAT BRITAIN AND IRELAND.

SNAP FASTENER.

Application filed December 10, 1924, Serial No. 755,023, and in Great Britain December 27, 1923.

This invention relates to snap fasteners of the kind consisting of a stud member to be attached to one edge of the garment to be fastened and a socket member to be attached 5 to the other edge adapted to receive and retain the head of the aforesaid stud member in order to fasten the said edges together.

In order that a garment may fit the wearer and set properly when fastened it is essential 10 that the stud and socket members of the fastener be attached to the edges of the garment precisely in their proper relative positions and the object of the present improvements is to provide a snap fastener of such a construction as will enable its members to be readily attached to a garment in the correct relative positions in the first place temporarily by means of a pin whereafter they or one of them (if the other had been permanently 15 attached before fitting) can be secured in place by sewing or equivalent means.

These improvements consist in providing the dome of the socket member with transverse holes at or near the bottom of the socket 20 for the passage of a pin for the purpose of temporarily attaching it to a garment while the edges to be fastened are in their correct relative positions, and to provide the base of the stud member with sewing-on holes 25 through which a pin may similarly be passed while the said edges are in the position it is desired they shall occupy when the fasteners are permanently attached. For this purpose the base of the stud member is provided with 30 depressions extending from the sewing-on holes to its edge.

In practice one of the members of the fastener, the stud member for instance, is sewn on to the under edge of the garment 35 with the unattached socket member in engagement with the stud. The outer edge of the garment is now placed over the inner edge in the position it is intended to occupy in use and while in this position a pin is passed 40 through the material from the outside and transversely through the hereinbefore mentioned holes in the dome of the socket portion of that member and thereafter through the material again so as to temporarily attach it 45 to the said outer edge until the fitting operation is completed.

When the socket member is attached to the inner edge the stud is first caused to engage it whereafter the outer edge is placed over

it in the desired position and a pin similarly 55 passed through the material and the holes in the base of the stud member so as to temporarily attach it to the said outer edge. After both members of the fastening (both of which may be at first temporarily attached to the 60 respective edges in the manner hereinbefore described) have been placed in position they may be sewn on before the pins are removed.

We will now proceed to more particularly 65 describe our invention with the aid of the accompanying drawings, in which—

Fig. 1 is a section through the improved snap fastener in which both the stud and socket members are provided with holes for temporary attachment to the edges of the 70 parts to be fastened together.

Fig. 2 is a section through the improved snap fastener in which the stud member only is provided with holes for temporary attachment to the outer edge of the parts to be fas- 75 tened together.

Fig. 3 is a plan and Fig. 4 an elevation of the stud member shown in Fig. 2.

Fig. 5 is a section through another arrangement of the improved snap fastener in which so the socket member only is provided with holes for temporary attachment to the outer edge of the parts to be fastened together, and

Fig. 6 is a plan and Fig. 7 an elevation of the socket member shown in Fig. 5. 85

According to the construction shown in Fig. 1 the base *a* of the stud member *b* is domed and provided with depressions *c* (see Figs. 3 and 4) between the outer edges of the sewing-on holes *d* and the outer edge of the 90 said base so as to enable a pin *e* to be passed through two of the said holes *d* for the purpose of temporarily attaching it to the material *h*.

The socket member *g* is also provided with 95 two holes *k* (see Fig. 7) diametrically opposite each other at or near the bottom of the socket so as to enable a pin *e*¹ to be passed horizontally through the said holes *k* for the purpose of temporarily attaching the socket 100 part to the material *i*.

According to this arrangement the stud member *b* is at first temporarily attached to the inner edge *h* of the garment by means of the pin *e*. The socket member *g* is next caused 105 to engage the stud member *b* whereafter the outer edge *i* of the garment is adjusted to the position it is desired to occupy when the said

garment is fastened. A pin e^1 is finally passed through the holes k in the dome j of the socket (whose position may be readily felt through the material) after passing through the said material.

After the positions of all the stud and socket members of the fasteners on a garment have thus been ascertained they can be sewn on before the pins are removed.

10 According to the construction shown in Figs. 2 to 4 the base a of the stud member b is domed and provided with depressions c between the outer edges of the sewing-on holes d and the outer edge of the said base 15 so as to enable a pin e to be passed through two of the said holes d for the purpose of temporarily attaching it to the material f .

According to the arrangement shown in 20 Figs. 2 to 4 an ordinary socket member g is sewn to the inner edge h of the garment in the usual way. The unattached stud member is then inserted into the socket and the outer edge i of the garment adjusted to the 25 position it is desired to occupy when the said garment is fastened. A pin e is then passed through two of the holes d in the base a whose position may be ascertained through the material f by the depressions c that may be felt through the said material.

30 After the positions of all the stud members of the fasteners on a garment have thus been ascertained they can be sewn on before the pins are removed.

According to the construction shown in 35 Figs. 5 to 7 the dome j of the socket member g is provided with two holes k diametrically opposite each other at or near the bottom of the socket so as to enable a pin e to be passed horizontally through the said holes k for the 40 purpose of temporarily attaching the socket to the material f .

According to the arrangement shown in the 45 said Figs. 5 to 7 an ordinary stud member b is sewn to the inner edge h of the garment in the usual way. The unattached socket member g is then caused to engage the stud b and the outer edge i of the garment adjusted to the desired position. A pin e is now inserted

through the holes k in the dome j of the socket 50 (whose position may be readily felt through the material) after passing through the said material.

After the positions of all the socket portions of the fasteners of a garment have thus 55 been ascertained they can be sewn on before the pins are removed.

It will be understood that both the stud and socket members of the improved snap fastener may in some cases be provided with pinning-on holes.

We claim:

1. A snap fastener comprising a stud member and a co-operating socket member, holes in the base of the socket member for securing it to one of the parts to be fastened together, sewing-on holes that extend up the sides of the stud portion, situated on diametrically opposite sides of the base of the stud member, depressions in the outer edge of the base 65 of the stud member in line with the aforesaid holes to enable a pin to be inserted transversely through them and the part to which the stud member is to be secured to enable that member to be temporarily attached 70 thereto while the correct position for its permanent attachment is being ascertained substantially as set forth.

2. A snap fastener comprising a stud member and a co-operating socket member, holes 80 in the base of the socket member for securing it to one of the parts to be fastened together, the stud member having a dome between its base and the stud portion, sewing-on holes 85 in the base on opposite sides of the stud member that extend into the sides of said dome, depressions in the outer edge of the base of the stud member in line with the aforesaid holes to enable a pin to be inserted transversely through them and the part to which 90 the stud member is to be secured to enable that member to be temporarily attached thereto while the correct position for its permanent attachment is being ascertained substantially as set forth.

CLAUDE MONTAGU TAYLOR.

EDWARD THOMAS WARMINGTON REED.
